UNITED STATES PATENT OFFICE

KARL FASSNACHT, OF PROVIDENCE, RHODE ISLAND, ASSIGNOR TO SPEIDEL CHAIN CO.,
A FIRM COMPOSED OF FREDERIC SPEIDEL AND EUGEN SPEIDEL, BOTH OF PFORZHEIM, GERMANY, DOING BUSINESS IN PROVIDENCE, RHODE ISLAND

CHAIN

Application filed October 18, 1927. Serial No. 226,908.

This invention relates to an improved construction of ornamental chain; and has for its object to provide a chain of this improved form of a plurality of sheet metal links, each 5 link comprising a relatively broad faced body portion formed of halves connected by a bendable neck portion and folded at the neck to lie one upon the other, the body halves being slotted longitudinally to permit 10 threading of one of the halves therethrough in connecting the links together.

A further object of the invention is to form these halves concavo-convex in cross section so that when one is folded upon the other 15 only their marginal edges meet thus imparting to the broad surface of the link a domed-shape or oval appearance, which renders it handsome and attractive.

A still further object of the invention is 20 the doming of the body portion of each link to a thickness substantially the outside diameter of the connecting eye member thereby presenting a smooth broad bearing surface to the arm of the wearer to prevent 25 abrasive action which might occur if the eye member were of a width greater than that of the body members of the links.

The invention further consists in the forming of a very narrow slot thru the body 30 halves, the slot being of a width just sufficient to permit passage of one of the body halves therethrough, the slot being enlarged at one end to receive the loop shaped neck portion and permit a free swinging movement of the 35 neck therein.

With these and other objects in view, the invention consists of certain novel features of construction as will be more fully described, and particularly pointed out in the 40 appended claim.

In the accompanying drawings:

Fig. 1 is a top view showing a plurality of links of my improved chain connected 45 together.

Fig. 2 is an edge view of the links illustrated in Fig. 1.

Fig. 3 shows one of the link members with its halves extending and connected by the 50 narrow neck portion.

Fig. 4 is a sectional edge view on line 4—4 of Fig. 3.

Fig. 5 is a sectional edge view showing two of the links connected together.

Fig. 6 is a section on line 6—6 of Fig. 5 thru one of the links and illustrating the dome shape of the body halves meeting at their marginal edges.

Fig. 7 is a perspective view illustrating the edge of one of the halves as being passed 60 thru the slot in the body halves of another link.

Fig. 8 is an edge view showing the broad surface of the domed halves as resting upon the arm of the wearer.

It is found in the practical construction and use of ornamental chains of this character which may be used as bracelets, neck chains, girdles or for other uses, preferably for personal wear, of advantage to provide 70 the links with a broad or extended bearing surface which may be smooth to lie against the delicate skin of the wearer without abrading the same and so construct the links of such a chain that they are substantially the 75 same in general dimensions and may be connected together by a simple threading and folding operation and without the use of solder and still obtain a chain which is very 80 strong and flexible; and to accomplish this in a simple and attractive way, I have blanked each link from sheet stock having two body halves connected by a bendable neck portion, the bendable neck portion also serving as a connecting member for the different body 85 links, each body member being slotted to permit the threading of the body half of the next adjacent link, the slot being preferably enlarged at one end to receive the connecting neck portion and permit its free movement 90 therein; and the following is a detailed description of the present embodiment of my invention and showing one construction of chain links by which these advantageous results may be accomplished:—

With reference to the drawings, 10 designates the body halves of a link which are blanked from sheet stock and connected together by a bendable narrow neck portion 11. The outline of these body halves being 100

preferably ornamental in shape and these body halves are preferably struck into a concavo-convex shape in cross section to form this body link when the halves are folded 5 one upon the other into a dome or oval shaped body in cross section, of grace and beauty; also providing an oval or rounded broad engaging surface to rest upon the delicate arm of the wearer without abrading the same.

10 Each of the halves of this body portion is slotted as at 12, the slots extending longitudinally thereof and each of these slots is of a width substantially the thickness of the stock of the next adjacent link plus the increased thickness due to the doming of the 15 halves so as to just permit a half to be passed thru this slot in the assembly of the parts.

One end of this slot 12 is preferably enlarged as at 13 to receive the connecting neck 20 portion 11 of the next link and permit it to lie crossways therein and swing laterally to render the chain flexible and its links to swing in any direction relative to the link to which it is attached. This neck portion is 25 folded into eye-shape so that it will permit this free relative movement of the links and also to serve to bind the free ends of the folded halves together against separation.

By the doming of the body portion of these 30 links, or forming it oval, the thickness of the body is substantially equal to the outer diameter of the eye portion 14 so that when lying flat the broad face of the body portion will touch and form a broad faced support 35 instead of resting upon the narrow edge of the eye or loop 14, which would be the case if the halves were not domed.

By forming my improved ornamental chain of links having broad surfaces, the 40 links may be shaped in any desired ornamental form and their broad surfaces are well adapted to receive ornamentation to render more attractive the appearance of the chain.

45 The foregoing description is directed solely towards the construction illustrated, but I desire it to be understood that I reserve the privilege of resorting to all the mechanical changes to which the device is susceptible, the invention being defined and limited only by the terms of the appended claim.

I claim:

An ornamental chain formed of a plurality of sheet metal links each comprising 55 a relatively broad faced body portion of ornamental outline formed of integral halves of concave-convex shape in cross section with the convex surface disposed outwardly and connected by a bendable neck portion, and 60 folded at the neck with their marginal edges meeting, to form an oval shaped body in cross section, said body halves each having a longitudinal slot of a width just sufficient to permit the passage of one of the link body 65 halves edgewise therethrough, said slots be-

ing enlarged at one end to receive the neck portion of an adjacent link, the enlargement being arcuate to permit pivotal movement, said movement in the plane of the links being limited by adjacent edges of the body portions.

In testimony whereof I affix my signature.

KARL FASSNACHT.
